UNITED STATES PATENT OFFICE.

CARL HEINRICH THOMAS, OF NEUGERSDORF, ASSIGNOR TO C. A. ROSCHER,
OF ALTGERSDORF, GERMANY.

SHEDDING MECHANISM FOR LOOMS.

SPECIFICATION forming part of Letters Patent No. 517,129, dated March 27, 1894.

Application filed December 19, 1892. Serial No. 455,963. (No model.) Patented in Germany November 7, 1891, No. 63,815.

To all whom it may concern:

Be it known that I, CARL HEINRICH THOMAS, a subject of the Emperor of Germany, residing at Neugersdorf, in the Kingdom of Saxony, Germany, have invented certain new and useful Improvements in Shedding Mechanism for Looms, (for which Letters Patent in Germany, No. 63,815, bearing date November 7, 1891, were granted to C. A. Roscher, in

10 Altgersdorf, Germany,) of which the following is a specification.

The object of my invention is to provide shedding mechanism by which the heddles of a loom harness are positively operated through 15 the introduction of pattern cards and cylinder; and for this purpose I provide mechanism to hold jacks, which are adapted to operate with their connecting devices the heddles of a loom harness, positively out of contact with the moving members of the shedding mechanism, when so required by the pattern cards.

The invention is illustrated in the accompanying drawings, in which—
25 Figure 1 is a side elevation partly in section showing the shedding mechanism mounted in a frame supported by the loom proper, and also the harness. Fig. 2 is a view showing one of the swinging guide bars in elevation. Figs. 3 and 4 show one of the swinging guide bars in side elevation and also its operations. Figs. 5 and 7 are side elevations of the shedding mechanism showing the different positions of the operated parts mounted 30 in the frame supported by the loom and Fig. 35 6 is a plan view of the shedding mechanism.

Referring now to the drawings for a further description of my invention, S are the heddles of a loom harness to be operated by 40 my improved shedding mechanism assembled and mounted in a frame adapted to be attached to any kind of loom. Each of these heddles S is operated by cords attached to opposite edges of the heddle and a lever S' ful- 45 crumed to the frame of the loom in the usual, or any preferred manner, so that when one cord is drawn in one or the other direction,

the heddle pertaining thereto may be raised or lowered, or in other words, the shed may be opened or closed.

To operate the heddles S to form certain and predetermined figures in the fabric, cards c⁸ fed over a cylinder C are employed in the usual, or any preferred manner, to cause the engagement or disengagement of certain devices to be presently described.

On top of the loom are secured standards F and F' held together by cross pieces f, f' q and q' and at the rear of said standards is journaled a shaft h, bearing at its ends and 60 outside of the standards two levers H, whereof one is provided with an extension h' to which a connecting rod h² is attached to oscillate the levers H and the similar disposed levers K hinged at their centers at the front 65 ends and outside of the standards F and F' by studs k. Each set of levers H and K at opposite sides of the standards F and F' are connected by the links v so that the levers H and K move in unison. The two levers K are 70 connected at their upper ends to a cross bar r and at their lower ends to a similar bar r', for purposes to be described. In the standards F and F' between the levers K and H are formed ways m² and m³ for guiding knives 75 m located at the top of the standards and knives m' located near the bottom of the said standards, and these knives are connected to the respective ends of the levers H by links z and z'.
80

For each heddle S is provided an arm l rotatably mounted on a cross bar o and guided by a slotted connection as at o', and the top cord of each heddle is connected to a depending harness lever w hinged on a cross rod o² 85 of the standards F and F', and each of these levers w is connected to its corresponding arm l by a slotted connection as shown at u. To an extension of each jack arm l is pivoted a jack lever i carrying at its opposite ends 90 jacks p and p' which are adapted to engage with their hooked ends the knives m and m' before mentioned. A rod or shaft d is provided between the standards F and F' upon

which a card frame D is rotatably mounted in the usual, or any preferred manner, and this frame D receives an oscillatory motion through link d' from an eccentric of the loom, 5 not shown. The card cylinder C is rotated by any suitable and known mechanism, for instance a pawl on one of the standards and a ratchet wheel on the shaft of the cylinder may be used so that when the card cylinder 10 C is descending by the manipulation of the frame D, and after the needles n or n' have left the cards thereof, the ratchet comes in contact with the pawl and drives the cylinder around to present another card at its upper 15 face. Directly above this card cylinder C are provided vertical needles, which are held in the guides N and N' of the frame, there are two needles n and n' for each arm l , and one needle for each jack p and p' ; the 20 projection g on the needles n are adapted to engage the upper jacks p , while the projections or hubs g' on the needles n' engage the jacks p' , all the needles n and n' however pass through long slots p^3 provided in the 25 jacks p and p' , to allow a sliding movement of the jacks caused by the knives m or m' , while the needles are held in their guides N and N'.

Above the two series of jacks p and p' are 30 mounted swinging guide bars s and s' which are attached to the lower ends of arms b^2 fastened to rock shafts b and b' . These bars s and s' are located above the hooked ends of the jacks p and p' and are adapted to slide 35 under the same, when the said jacks are lifted, by the action of springs b^3 attached to the upper end of the arms b^2 and a member of the machine frame.

Stop arms c and c' on the rock shafts b and 40 b' impinging against the cross bars, q and q' of the standards F and F' are employed to limit the movement of the swinging guide bars s and s' under the influence of the springs b^3 . These latter are moved either in or out of the 45 path of the jacks p and p' by bent levers a and a' adjustably attached by screw nuts to the links z and z' .

In describing the operation of my improved 50 shedding mechanism, the co-operation of the devices pertaining to one harness heddle will be stated.

In Fig. 5 are shown the positions of the different devices heretofore described, when the shed is open, and in Fig. 7 when the shed 55 is closed. When the shed is closed the jack levers i lie against the cross bars f and f' as in Fig. 7.

To open a shed, the needles n and n' enter 60 perforations in the cards c^3 as the cylinder C is forced upward by its frame D and link d' , so that the jacks p and p' remain in their lowest positions as shown in Fig. 5; the knife m' therefore is permitted to engage the jacks p' and draw the same through the motion of 65 the rock shaft b and levers H to the position

as shown in Fig. 5. The lower ends of the respective jack levers i are thereby withdrawn from the cross bar f' , while the upper ends thereof still remain in contact with the bar f . The arms l are thereby drawn at their 70 upper ends to the right in Fig. 5 and the depending levers w connected to the arms l at u move also in that direction thereby raising the heddles S connected by cords to the respective levers w . If it is desired to keep 75 the shed open for the next pick or number of picks, the needles n and n' must again enter apertures in the card c^3 , so as not to raise the jacks p and p' out of their lowest position; the levers H now moving in the opposite direction from that described before, the jacks p are drawn toward the right in Fig. 5 by the knife m , while the jacks p' are drawn toward the left by the bar r' impinging against the lower ends of the jack levers i , without, however, moving the center or pivoted connection between the respective jack levers i and their arms l , the jack levers i simply moving 80 idle about their pivotal connection y with their respective arms l . If heddles S are to 85 be depressed, the corresponding needles n or n' are raised by a non punctured part of the cards c^3 on the cylinder C while the latter is moved upward by its frame D as described, and the hub or projection g or g' on the needle 90 elevates the respective jack p or p' . At the same time the desired jack is lifted, the levers H commence to turn say with their upper end to the right to release the bent lever a of the link z to allow the swinging guide 95 bar s to be shifted under the hooked ends of the elevated jacks p by the springs b^3 as shown in Figs. 4 and 7. The hooked ends of the jacks p now resting on the swinging guide bar s impinge against the cross bar q and the 100 levers H now turning farther in the direction stated, also turn the levers K in the same direction, and cause the thereto affixed cross bar r' to move the jack levers i in the position shown in Fig. 7 thereby pushing the upper ends of the arms l and with it the lower ends of the depending levers w toward the left Fig. 7, closing the shed or rather lowering the desired heddle or heddles S. If it is 105 desired to keep the shed closed for any time, the jacks p and p' are alternately lifted, by the needles n and n' and the bars s or s' hold 110 the respective jacks in their raised positions, so that the knives m or m' pass freely under the said jacks p or p' .

Having thus described the nature and object of my invention, what I claim as new, and desire to secure by Letters Patent, is—

In shedding mechanism for looms, the combination with the dobby frame, the pivoted 125 harness lever w , jack lever i , jack arm l connecting said levers, two series of hooked jacks, knives, and means for operating said knives, pattern cards and cylinder, rock shafts b b' provided with arms b^2 , bars s s' 130

attached to the said arms b^2 and adapted to lock the jacks in raised or lowered position, springs connected to the arms b^2 , stop arms $c c'$ on the rock shafts to limit the movement

5 of the bars $s s'$ under the influence of the springs, bent levers $a a'$ attached to the operating means for the knives and moving to contact with the arms b^2 to rock the shafts $b b'$ and unlock the said jacks to allow the

pattern cylinder to indicate, substantially as 10 described.

Signed at Zittau, Saxony, this 25th day of October, 1892.

CARL HEINRICH THOMAS.
